(57) **CLAIM**

The ornamental design for an incline sorter, as shown and described.

DESCRIPTION

FIG. 1 is a front perspective view of a incline sorter showing the new design;

FIG. 2 is rear perspective view thereof;

FIG. 3 is a right side view thereof;

FIG. 4 is a left side view thereof;

FIG. 5 is a front view thereof;

FIG. 6 is a rear view thereof;

FIG. 7 is a bottom view thereof; and,

FIG. 8 is a top view thereof.

The broken lines showing portions of the inside of FIG. 7 are included for the purpose of showing surfaces that form no part of the claimed design.
